SWITCH FOR HIGH-FREQUENCY
ELECTRICAL OSCILLATIONS

Dennis Clark Espley, North Wembley, England,
assignor to The General Electric Company Limited, London, England

Application March 30, 1946, Serial No. 658,404
In Great Britain March 7, 1945

Section 1, Public Law 690, August 8, 1946
Patent expires March 7, 1965

8 Claims. (Cl. 178—44)

1

This invention relates to switches for high-frequency electrical oscillations and is an improvement in or modification of switches of the type described and claimed in United States Patent No. 2,404,832, issued July 30, 1946, in the name of Dennis Clark Espley, whereinafter referred to as the parent specification.

The parent specification describes and claims a switch for high-frequency oscillations of wavelength λ , corresponding to frequency f , comprising a uniform line substantially of length $q\lambda/4$, where q is an integer, having its members connected at one end to a pair of terminals, being the terminals the impedance between which the switch renders alternatively very large or very small, means for approaching a conductor to the other, open, end of the line so as to provide an impedance shunting the said open end which is the impedance of a capacity C , and an impedance element X of such a nature and value and constantly associated with the said pair of terminals in such a manner that, when the said conductor is near the said open end, the impedance between the said pair of terminals assumes substantially one of the values zero and infinity and, when the said conductor is far from the said open end, the impedance between the said pair of terminals approaches the other of the said values.

In some circumstances it may not be possible for the length of the uniform line to be $q\lambda/4$, or it may be desirable for it to be different from $q\lambda/4$, for example, in view of dimensional limitations or requirements in the apparatus of which the switch forms part, and the object of this invention is to provide means for obtaining the required switching action when the length of the line is substantially different from $q\lambda/4$.

Figure 1 of the drawing is a schematic diagram of a switch according to the invention.

Figure 2 is a schematic diagram, with some parts in section, of another embodiment of the invention.

The principles underlying the invention will now be described with reference to the accompanying drawing which shows schematically a length L of uniform line, of characteristic impedance Z_0 , connected across the said pair of terminals 1, 2 and terminated with an impedance Z_2 .

Z_0 and Z_2 are impedance elements permanently

2

associated in parallel and series respectively with the terminals 1, 2.

If Z_1 is the impedance looking into the terminals 1, 2 then when $Z_p=\infty$ and $Z_s=0$,

$$Z_1 = \frac{Z_0(Z_2 + jZ_0 \tan \theta)}{(Z_0 + jZ_2 \tan \theta)} \quad (1)$$

where $\theta = 2\pi L/\lambda$. This is the well-known equation for the input impedance of a length of uniform line terminated with impedance Z_2 .

If Z_p and Z_s have other values, we have from (1) and the ordinary rules for combination of impedance in series and in parallel

$$\frac{1}{Z_1 - Z_s} = \frac{1}{Z_p} + \frac{(Z_0 + jZ_2 \tan \theta)}{Z_0(Z_2 + jZ_0 \tan \theta)} \quad (2)$$

If Z_A is the value of Z_1 when $Z_2=\infty$ (corresponding to the said conductor withdrawn from the open end of the line) and Z_B is the value when $Z_2=1/j\omega C$ (corresponding to the said conductor approached close to the open end of the line) where $\omega=2\pi f$, then

$$\frac{1}{Z_A - Z_s} = \frac{1}{Z_p} + \frac{1}{Z_0} (j \tan \theta) \quad (3)$$

and

$$\frac{1}{Z_B - Z_s} = \frac{1}{Z_p} + \frac{j(Z_0 \omega C + \tan \theta)}{Z_0(1 - Z_0 \omega C \tan \theta)} \quad (4)$$

To obtain perfect switching across the terminals 1, 2, we must have $Z_A=0$ or ∞ and $Z_B=\infty$ or 0 respectively. If these pairs of values of Z_A and Z_B are substituted into Equations 3 and 4, then for any particular value of $\tan \theta$ the equations may be solved for Z_s and Z_p ; i. e. for any particular length of line it is possible to find from these equations values of Z_s and Z_p which will give rise to the switching action required; the aforesaid object of the invention may thereby be attained.

According to the invention a switch for high-frequency electrical oscillations of wave length λ , corresponding to frequency f , comprises a uniform line of length L appreciably different from $q\lambda/4$, where q is an integer, having its members connected at one end to a pair of terminals, means for approaching a conductor to the other, open, end of the line so as to provide an impedance shunting the said open end which is the impedance of a capacity C , and one or more impedance elements of such nature and such a value and constantly associated with the said terminals in

such a manner that when the said conductor is near the said open end the impedance between the said pair of terminals assumes substantially one of the values zero and infinity and when the said conductor is far from the said open end the impedance between the said pair of terminals assumes substantially the other of the said values.

In the parent specification the length of line specified is $q\lambda/4$ as aforesaid. If q is odd then $\tan \theta = \infty$ and we have the switching action $Z_A = 0, Z_B = \infty$ if

$$Z_s = 0, \text{ and } Z_p = -jZ_0^2\omega C \quad (5)$$

If q is even, $\tan \theta = 0$ and we have the switching action $Z_A = \infty, Z_B = 0$ if

$$Z_s = -j/\omega C, \text{ and } Z_p = \infty \quad (6)$$

These are the arrangements described in the parent specification.

These arrangements have the advantage that only one impedance element is required whereas with arrangements in accordance with the invention two impedance elements, one in series and one in parallel, will in general be required; there are, however, special cases of the arrangement in accordance with the invention where only one impedance element is required. These special cases require a particular length of line, as will now be shown, and may be useful where this particular length is possible or desirable.

Thus putting $Z_s = 0$ in Equations 3 and 4 it follows that the switching action $Z_A = \infty, Z_B = 0$ will be obtained if

$$Z_p = jZ_0^2\omega C, \text{ and } \tan \theta = 1/Z_0\omega C \quad (7)$$

In this arrangement Z_p is inductive and the minimum value of L is less than $\lambda/4$.

Putting $Z_p = \infty$ in Equations 3 and 4 it follows that the switching action $Z_A = 0, Z_B = \infty$ will be obtained if

$$Z_s = -j/\omega C, \text{ and } \tan \theta = -Z_0\omega C \quad (8)$$

In this arrangement Z_s is capacitative and the minimum value of L lies between $\lambda/4$ and $\lambda/2$.

The impedance elements used in accordance with the invention may be lumped impedances or they may be lengths of transmission line, in the same way as with the arrangements in accordance with the parent specification; also the said conductor may be a plate as described in the parent specification.

When a switch in accordance with the invention is branched off a main transmission line in order alternatively to permit oscillations to travel freely down the line or greatly to attenuate the oscillations, a plurality of switches each in accordance with the invention and acting as attenuators in series may be provided at spaced points, preferably separated by distances $\lambda/4$, along the line in order to increase the attenuation, as described in United States Patent No. 2,401,863, issued June 11, 1946, in the name of Dennis Clark Espley in connection with the parent application.

This arrangement is shown schematically in Fig. 2 of the accompanying drawing which shows a section through the relevant parts.

Here the main concentric transmission line consisting of outer conductor 1 and inner conductor 2 is adapted to convey electrical oscillations from a source 3 to a power consuming device 4 and has branched off from it at points spaced $\lambda/4$ apart two switches in accordance with the invention; these switches consist of concentric line stubs of lengths L having outer conductors 5, 5' joined to the outer conductor 1 and

inner conductors 6, 6' joined to the inner conductor 2 through transmission-line stubs represented by the dotted circles 7, 7' acting as impedance elements in series with the input of the switching stubs; these transmission-line stubs may consist of parallel wire lines surrounded by a cylindrical conductor connected to the conductor 1 as described in the parent specification.

The first switching stub is branched off at a distance $\lambda/4$ from the end of the main transmission line to which the source 3 is connected.

Also branched off from the main transmission line at the same points as the said switches are concentric line stubs consisting of outer conductors 8, 8' joined to the outer conductor 1 and inner conductors 9, 9' joined to the inner conductor 2 so as to act as impedance elements in parallel with the input of the switching stubs.

The length of each switching stub is appreciably different from any multiple of $\lambda/4$ and the lengths of the stubs providing the series and parallel impedance elements are adjusted with respect to L as indicated by Equations 3 and 4 to provide the necessary values of Z_s and Z_p to produce the required switching action on the approach or removal of the conducting plates 10, 10' from the open ends of the switching stubs.

I claim:

1. A switch for high-frequency oscillations of frequency f comprising a stub including a concentric uniform line of length L substantially different from $q\lambda/4$ where q includes all integers of odd and even gender, and λ is the wave length along the said line corresponding to the frequency f , the members of said stub being adapted to be connected at one end of the stub to another uniform line which the switch is to control, the second end of said stub being open, a conductor relatively movable with respect to the open end of said stub between a first position in which said conductor and the open end of said stub are remotely spaced and a second position in which said conductor and the open end of said stub are closely spaced, whereby said conductor gives rise to a capacitative impedance of value C in said second position shunting the open end of said stub, and at least one compensating impedance element permanently electrically connected to said first end of the stub, the number of impedance elements and the type and value of each impedance element and its connection to said first end of the stub being such with respect to the frequency f , the value of L , the impedance C and the characteristic impedance Z_0 of the stub, that when said conductor is in one of said positions the impedance across said first end of the stub is substantially zero and when said conductor is in the other of said positions the impedance across said first end of the stub is substantially infinity.

2. A switch according to claim 1 wherein the length L of the said stub is $\lambda\theta/2\pi$ where θ in radians is $\tan^{-1}(1/2\pi/Z_0C)$ and comprising an inductive compensating impedance element of inductance Z_0^2C connected in parallel with the said first end of the said stub.

3. An electric system comprising a uniform transmission line connected at one end to a source of high-frequency energy and at the other end to a current consuming device, said system including a switch as set forth in claim 2 for controlling the supply of energy from said source to the current consuming device, the stub of said switch being connected to said uniform transmission line at an integral number of quarter wave lengths from that end of the transmission line

which is connected to the source of high-frequency energy.

4. A switch according to claim 1 wherein the length L of the said stub is $\lambda\theta/2\pi$ where θ in radians is $\tan^{-1}(-2\pi f Z_0 C)$ and comprising a capacitative impedance element of capacity C connected in series with the said first end of the said stub.

5. An electric system comprising a uniform transmission line connected at one end to a source of high-frequency energy and at the other end to a current consuming device, said system including a switch as set forth in claim 4 for controlling the supply of energy from said source to the current consuming device, the stub of said switch being connected to said uniform transmission line at an integral number of quarter wave lengths from that end of the transmission line which is connected to the source of high-frequency energy.

6. An electric system comprising a uniform transmission line connected at one end to a source of high-frequency energy and at the other end to a current consuming device, said system including a switch as set forth in claim 1 for controlling the supply of energy from said source to the current consuming device, the stub of said switch being connected to said uniform transmission line at an integral number of quarter wave

lengths from that end of the transmission line which is connected to the source of high-frequency energy.

7. A switch according to claim 1 wherein at least one said compensating impedance element is provided by a length of transmission line.

8. An electric system comprising a uniform transmission line connected at one end to a source of high-frequency energy and at the other end to a current consuming device, said system including a plurality of like switches each as set forth in claim 1 for controlling the supply of energy from said source to the current consuming device, the stubs of said switches being connected to said uniform transmission line at an integral number of quarter wave lengths from each other and from that end of the transmission line which is connected to the source of high-frequency energy.
